LINES FOR TRAWL NETS

Frank J. Luketa, 5567 Greenwood Ave., Seattle 3, Wash.
Filed Apr. 9, 1962, Ser. No. 186,086
9 Claims. (Cl. 43—9)

In a companion application entitled Lines for Trawl Nets, Serial No. 186,087 filed April 9, 1962 there is described and claimed a line intended for use as a long curtain line for instance, which is formed with built-in means to do either or both of two things, namely, to buoy up (or to depress) the line, and to urge the line out of a catenary curve towards straightness. This is accomplished by encasing a steel cable core within a casing molded of rubber to define hydrofoil and/or water reaction surfaces. The netting of the curtain must be secured all along its edge to the line, or specifically to the casing, in a manner to avoid disturbance of the force-producing functions of such surfaces, yet strongly and accurately.

Another companion application entitled Lines for Trawl Nets, Serial No. 186,085 filed April 9, 1962, discloses and claims a hanging line assembly particularly suited for use with lines of the general character of Serial No. 186,087 and which have a bar-cut edge which is hung from the line.

The present invention deals specifically with the securing of a line to a netting panel, to the ends indicated hereinabove, when the netting panel's edge is point-cut, as it would be normally in a bottom trawl net curtain. Subject-matter common to Serial No. 186,085 and to this application will be claimed herein.

Also, since it is desirable to make such lines in sections, capable of being joined end to end with like sections to constitute a line of required length, it is an object to use securing means between the line and the mesh panel that are best suited for use in the line sections of relatively short length, and suited for use according to a novel method hereinafter explained.

Further objects will appear hereinafter.

FIGURE 1 is an isometric view of a bottom trawl net, which is the type to which this invention is particularly applicable, partly broken away, but drawn to a scale too small to show details of the connection between the curtains and the curtain lines.

FIGURE 2 is an enlarged isometric detail of the lower edge of a curtain, illustrating why the curtain panels should be point-cut at top and bottom edges.

FIGURE 3 is a top plan view, to a very small scale, of a net lacking the catenary-correcting means that is built into the line of this invention (as explained in said application Serial No. 186,087), and which to some degree complicates the problem of interconnecting the mesh panel and the line, and FIGURE 4 is a similar view of the net which incorporates the catenary-correcting means, for comparison.

FIGURE 5 is a top plan view of the forward portion of the curtain of FIGURE 3, and FIGURE 6 is a sectional view of the same at the line 6—6 of FIGURE 5.

FIGURE 7 is a top plan view of the same forward portion of the curtain of FIGURE 4, and FIGURE 8 is a sectional view of the same at the line 8—8 of FIGURE 7.

FIGURE 9 is an isometric view of a portion of the line with the curtain hanging limply, and showing certain of the details of this invention; FIGURE 10 is a like view, with the curtain inclined aft and down, as it would be in use.

FIGURE 11 is an enlarged isometric view of an end portion of a section, partly broken away, and showing further details of this invention in one embodiment.

FIGURE 12 is an elevational view of the limply hang-

2

ing curtain, at the two sides of a joint between sections, and FIGURE 13 is a plan view of the same.

FIGURES 14, 15, and 16 are all sections at the line 15—15 of FIGURE 12, FIGURE 14 illustrating a first step in the assembly of the line, FIGURE 15 illustrating the assembly completed but the curtain hanging limply, and FIGURE 16 illustrating the assembly being drawn forwardly through the water, in use.

FIGURE 17 is an elevational view, partly in section, of 10 a modified form of line, incorporating this invention.

FIGURE 18 is an elevational view, partly in section, showing a first step in the assembly of the modified form of line, and FIGURE 19 is an isometric view of the same.

FIGURE 20 is a sectional view, at the line 20—20 of 15 FIGURE 17, and FIGURE 21 is a sectional view at the line 21—21 of FIGURE 18.

The bottom trawl net chosen to illustrate this invention includes a codend 9 closed by a purse line 90 at its after end, its forward end being secured to and held open 20 by an expander ring 91. A funnel 92 diverges forwardly from the expander ring 91 to which it is secured, to an upper bosom 93 and lower bosom 94. Curtains 7 are secured at their after ends, at 70, to the sides of the funnel 92, and diverge widely forwardly. These curtains 25 hang from curtain lines 71 which extend from the upper bosom 93 to an anchorage at 72 upon doors 6, that cause the curtains to diverge by water reaction as the doors are towed by towing warps 60. A sweep line 84, buoyed up by occasional floats 84a, or by other suitable means, extends from mesh suspenders 8, or the connectors 86 to 30 which the suspenders are connected at their forward ends, to anchorage 72 at the door. The suspenders at their rear ends are distributed about the expander ring 91, and the sweep lines 84 and suspenders 8 in effect pull the 35 codend 9 forwardly over the bottom. Rolling bobbins 95 across the lower bosom hold this part of the net off the bottom, to prevent snagging.

The curtains 7 and the curtain lines 71 best illustrate the present invention. Each curtain line must support its 40 curtain above the bottom throughout its length, yet the lower edge of the curtain should drag the bottom. The curtain line might be buoyed up, and its tendency to assume a catenary curve, as illustrated in FIGURE 3, might be corrected by floats attached at intervals along the line, and of a type disclosed in my application Serial No. 150,577, filed November 6, 1961, but it is possible to incorporate in the line itself means to buoy it up and to cause the line to straighten from its catenary curvature, to assume somewhat the shape shown in FIGURE 4, either or both. A line of this nature is disclosed and claimed in said application Serial No. 186,087. It is with a line of this type that the present invention is concerned, more particularly with the assembly of the point-cut edge of a curtain or other netting panel with such a line.

50 By employing such a line all extraneous floats, anchored at intervals along the line, are dispensed with. There is then no tendency for them to interfere with reeling in of the net by the drum trawling method, nor for the floats to become entangled in the net. The catenary correction 55 is desirable because without it, the leading ends of a long curtain lie substantially in the line of advance, and the curtain does not, in this portion, incline rearwardly to block escape of fish over its upper edge, for the curtain will hang vertically, as shown in FIGURE 6, whereas if the line is more nearly straight throughout its length, as in FIGURE 4, the curtain will incline rearwardly and downwardly from the curtain line throughout its length, as in FIGURES 7 and 8, to trap all fish it encounters along the bottom.

70 The curtain line 71 is buoyed up by hydrofoil surfaces which include fin-like water reaction surfaces 73, blunt at the nose and cambered to a thin trailing edge, formed

upon a casing 76 molded of rubber or the like, enclosing a stranded wire core 74. Auxiliary hydrofoil surfaces 75, supported by outstanding and more or less helically disposed water reaction surfaces 77, serve to minimize drag. The surfaces 77 by water reaction as the line is drawn forwardly, tend to correct the catenary curvature. All this is more fully explained in application Serial No. 186,087. The lower edge of the curtain is held down by weights 5 (FIGURE 2) secured at intervals along this edge.

There is some slight distention of the curtain from top to bottom, and for this and other reasons it is best that the curtain have point-cut or selvage edges at top and bottom, and that sections of curtain panels be joined at their ends by joining bar-cut edges by connectors such as 4. The weights 5 are secured by engaging their supporting rings 50 (FIGURE 2) with one or two points of the mesh.

According to this invention the casing 76 is formed with an internal tunnel or passage 76a, of a size to receive the cable core 74. The casing might be molded about the core, but preferably the core is insertible within and removable from its passage 76a. One way for doing this is to slit the casing at 76b from its exterior to intersect the passage 76a, wherefore, the casing being of rubber or like resiliently elastic material, its slit portion may be opened, as in FIGURE 14, to receive the core, and will then close again. The slit, if it opens thus fully, should be in the trailing edge portion of the casing.

Reliance is not placed upon the resilience of the split casing to retain the core within the casing, nor does the construction as so far described provide a means to secure the curtain's edge to the line. To these ends projections or knobs 78 are formed on one of the slit portions of the casing 76, at intervals in its length, and the complementary portion of the casing has apertures 79 to pass the knobs 78. The latter are of sufficient length to project beyond the outer surface of the casing, and are there apertured, at 78a. The water reaction surfaces 77 at the same side of the casing are also apertured, at 77a, in alignment with apertures 78a when the casing is relaxed, as in FIGURE 15. Additional terminal knobs, designated 78b, similar in all respects to knobs 78, are provided at the end of each sectional length of the casing 76, where ends of adjoining lengths or sections are joined with a coupler 40.

After the core 74 is inserted within its passage 76a and the casing is relaxed, the knobs 78 pass through the apertures 79. Now the point-cut edge of the curtain 7 is placed along the line, and a hanging line 1 is threaded through the apertures 78a in knobs 78 and 78b, and through apertures 77a in elements 77, and through each point of the mesh it encounters. The knobs, or the water reaction elements located where a knob would otherwise protrude, are spaced lengthwise at intervals corresponding to the spacing between points of the mesh, that is to say, by a distance equal to the diagonal dimension of a mesh square, and the apertures 78a and 77a lie close to the exterior surface of the casing. In consequence the knobs may not pull out of their apertures 79, the hanging line is well protected by the casing, and the mesh points are accurately engaged and supported. The mesh hangs evenly from the several suspension points, and nowhere is it crowded nor stretched.

If it is preferred not to slit the casing to its exterior, the alternate construction of FIGURES 17 to 21 may be employed. Each sectional end of core 74 must have a swaged-on head 74a for clamping within a coupler 40 against tensional pull. The passage 76a may be sufficiently enlarged, as by the radial slit 76c, to pass the head 74a, as in FIGURES 18 and 21. Knobs 78c, the same in number, location, and spacing as the knobs 78 and 78b, are now integral with and project from the exterior surface of the unslit casing 76, and are similarly apertured at 78a for reception of the hanging line 1. Securement of the couplers 40 with the heads 74a secures the line sec-

tions together, and threading of the hanging line 1 through the points of the mesh and the apertures 78a and 77a secures the curtain and line together. The ends of the hanging line are suitably secured, as by swaged-on terminals 10 outside the terminal knobs 78b.

It will be noted that the curtains are formed of a plurality of sections, each complete with its mesh, curtain line, terminals or heads 74a for joining by the couplers 40, and hanging line. Weights 5 can also be in place upon each section. A quick-releasable fastener 4 joins the edges of adjacent sections. Should the mesh of any curtain section snag upon a bottom obstruction and tear, it is a matter of a couple of minutes, only, to disconnect the torn section at 40 and at 4 from adjoining sections, and to replace it with a complete replacement section, already equipped with all necessary elements, and of the same dimensions as the original section. The torn section can be repaired as opportunity presents itself, but more importantly, the restored net can be reset with little loss of fishing time.

The assembly is effected quite rapidly, and when complete is secure against accidental disengagement. Nevertheless, when disassembly is required, it is only necessary to remove a terminal 10 (by simply cutting it off) from the expendable hanging line, and the latter can be immediately withdrawn throughout the length of a section.

I claim as my invention:

1. In combination with a mesh curtain panel or the like, a line including a core and an external casing for the core, supporting means distributed lengthwise of the casing at spacings corresponding to the dimension of successive meshes of the panel along the same line, and engaging successive meshes to space them equally, said supporting means including a hanging line extending horizontally throughout its length, and engaged with meshes distributed along the panel's edge, and with the casing.

2. In combination with a mesh curtain panel or the like, a line including a cable core and a flexible casing surrounding the core throughout its length and slit lengthwise from its exterior to the core, to receive the core within said slit, and means for securing the edge of the panel to the casing when so received within the slit, including elements spanning and closing the slit outwardly of the core, and spaced lengthwise of the casing by distances corresponding to the dimension of successive meshes of the panel, in the same direction, said engaging means also including a hanging line engaged with the panel's edge and with the casing.

3. In combination with a mesh curtain panel or the like having a point-cut edge, a line including a core and a casing enclosing said core, elements projecting from the casing at spacings lengthwise of the casing corresponding to the spacings between successive points at the edge of the mesh, the several projecting elements having apertures, and a hanging line threaded through such apertures and through the successive points of the mesh's edge.

4. The combination of claim 3, wherein certain of the apertured projecting elements are water-reaction surfaces, and others are knobs.

5. The combination of claim 3, wherein all the apertures are aligned lengthwise of the line.

6. In combination with a mesh curtain panel or the like, having a point-cut edge, a line including a core and a casing of flexible material enclosing said core and slit lengthwise from its exterior to the core, knobs projecting across the slit from one side portion of the casing, the opposite side portion being apertured for the protrusion of said knobs, the knobs being spaced lengthwise of the casing in general correspondence with the diagonal dimension of the mesh squares, and being each apertured in its protruding portion, and a hanging line threaded through the apertures of the knobs and through intervening points along the panel's edge.

7. In combination with a mesh curtain panel or the like, having a point-cut edge, a line including a core and a casing of flexible material enclosing said core, the core having a passage for the core deformable and thereby

enlargeable for threading of the core through it, knobs projecting at one side of the casing and spaced lengthwise in general correspondence with the diagonal dimension of the mesh squares, and being each apertured, and a hanging line threaded through the apertures of the knobs and through intervening points of the mesh, along its edge.

8. The combination of claim 6, including further water reaction surfaces projecting from the casing intermediate certain knobs, and similarly apertured, the hanging line also passing through the apertures of the water reaction surfaces and through mesh points between the latter and adjacent knobs.

9. In a trawl net which includes a codend and curtains diverging forwardly from the codend, each curtain comprising a plurality of like mesh panels, a plurality of curtain line sections each of the same effective length as its mesh panel, coupler means for joining the ends of the suc-

cessive curtain line sections, and fastener means quickly releasable and reengageable disposed along the forward and rear edges of each mesh panel, engageable with like fastener means on adjoining panels to complete the curtain of indeterminate length, whereby a damaged curtain panel may be removed intact and replaced by a whole panel.
